UNITED STATES PATENT OFFICE.

HENRY CLAY BORGNER, OF PHILADELPHIA, PENNSYLVANIA.

DESIGN FOR A CENTURY MONUMENT.

SPECIFICATION forming part of Design No. 18,891, dated February 5, 1889.

Application filed November 27, 1888. Serial No. 292,033. Term of patent 14 years.

To all whom it may concern:

Be it known that I, HENRY CLAY BORGNER, a citizen of the United States, residing at Philadelphia, in the county of Philadelphia and State of Pennsylvania, have invented and produced a new and original Design for a Century Monument; and I do hereby declare the following to be a full, clear, and exact description of the invention, such as will enable others skilled in the art to which it appertains to make and use the same.

In the accompanying drawing, which forms part of this specification, the figure represents an elevation.

Reference being had to the drawing, A indicates the monument. The small numerals, 1 to 38, represent gradually-diminishing star-shaped sections, of which the monument is composed.

The numerals 1' to 23' indicate figures, busts, or statues.

B indicates one of five ornamental doorways in the base or crypt in the monument.

The whole design is arranged in tiers or stories, and each story is provided with a series of figures, as shown, a doorway, C, and a balcony, D, of which there are five in each story.

Having thus fully described my invention, what I claim is—

The design for a century monument composed of gradually - diminishing sections, courses, or spaces, arranged in tiers or stories, and each story having figures, a balcony, and a doorway, substantially as described and shown.

In testimony whereof I affix my signature in presence of two witnesses.

HENRY CLAY BORGNER.
